UNITED STATES PATENT OFFICE

129,159

DESIGN FOR A LEAD PENCIL OR SIMILAR ARTICLE

Henry Dreyfuss, New York, N. Y., assignor to
Eversharp, Inc., Chicago, Ill., a corporation of
Delaware

Application June 30, 1941, Serial No. 101,814

Term of patent 14 years

To all whom it may concern:

Be it known that I, Henry Dreyfuss, a citizen of the United States, residing at New York, in the county of New York and State of New York, have invented a new, original, and ornamental Design for Lead Pencil or Similar Article, of which the following is a specification; reference being had to the accompanying drawing, forming a part thereof.

In the drawing:

Fig. 1 is a perspective view of a lead pencil showing my new design;

Fig. 2 is a side elevational view; and

Fig. 3 is an end view looking at the lower end of Fig. 2.

I claim:

The ornamental design for a lead pencil or similar article, substantially as shown.

HENRY DREYFUSS.
